(57) CLAIM

The ornamental design for convertible bar and food station, as shown and described.

DESCRIPTION

FIG. 1 is a perspective view of a convertible bar and food station showing our new design, wherein the panels are positioned in front of the food station;

FIG. 2 is a front elevation view of FIG. 1;

FIG. 3 is another perspective view thereof, wherein the panels are positioned in front of the bar area; and,

FIG. 4 is a front elevation view of FIG. 3.

The broken lines shown are included for the purpose of illustrating the environment in which the article resides and form no part of the claimed design.

1 Claim, 4 Drawing Sheets
